Method of Patent.

The "schematic" referred to in these Letters Patent are making part of the same containing a description in the words of the said Barak Swift himself of his "Machine for Shearing Cloth."

This machine consists of a frame about fourteen feet in length and about four feet in breadth the bottom piece which is grooved or rabbeted for the carriage to run in and on which are four upright pieces with suitable rails and braces to support the main shaft and the wheels connected therewith together with a short low carriage which moves within the said frame on rollers, requires to be about seven feet in length three feet in height and two feet six inches in width, to which is attached lengthways two cylinders (each capable of receiving a whole piece of cloth) with say twelve legs, four front and four back, one to roll the cloth in, previous to its being sheared and from which the cloth passes over lengthways, across the top of the carriage where it is fastened between two rails with hooks on the top of the said carriage and is tightened by means of a windlass which has a cog wheel and dog fixed at the end of said carriage on brackets which are fastened two ends connected with one of the stretching rails the other of the rails are fixed to the carriage behind the second cylinder, the cloth then passes over the top of said carriage again it is sheared to the other cylinder on which it is rolled, and the far end of this carriage

is a cylinder covered with several thicknesses of cloth, and
is graduated at the end of a frame which may be
held by means of two screws at the end of the main frame
and at the same cylinder to the shear, and which being
pulled upwards in a ratchet and is held with the top of the
carriage the said second cylinder is raised one half of its
diameter above the top of the carriage, to support the shear
up to the bear size. The main shaft is put in motion
turning of a crank, so the shaft is given a large and a
small oscillating wheel the large one is connected by a
rope or cord to a small wheel at the end of a small
shaft, which goes slower by means of two unequal ones
connected to the steel spiral shear which cuts them in
a vibrating motion over the edge of the bed shear by
means of two unequal motors and which said shear is
immediately over the second cylinder and all of which
are fixed or suspended sideways on the carriage, the
small oscillating wheel or main shaft is connected with
the other oscillating wheel by rods or steeps one of which
is on the axis of the person which gives motion to the ca-
rriage by means of a rack, fixed shears, and as the person
is to move the same operation gives motion to the spiral
vibrating shear, which thereby performs the operation of
shearing the cloth in a way equal to the hand shear
and a youth four years or fifteen years of age can use
the improved machine performing four times the quantity,
having had a good and experienced workman can turn
out of hand by means of hand shear, a spring box is
fixed on the side of the main frame over the frame
to throw it out of gear so that the carriage may be
moved back. The spiral shear and its shaft together
with the bed shear is fixed in a frame in two arms
with shaft lying on guides so that the shear may

be raised up to fit the shell more readily over the
curved surface, to the meeting and. —
